UNITED STATES PATENT OFFICE.

JAMES CAVANAGH, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE-LASTING MACHINE.

1,163,600.

Specification of Letters Patent.

Patented Dec. 7, 1915.

Application filed March 5, 1914. Serial No. 822,663.

To all whom it may concern:

Be it known that I, JAMES CAVANAGH, a citizen of the United States, residing at Boston, in the county of Suffolk and State 5 of Massachusetts, have invented certain Improvements in Shoe-Lasting Machines, of which the following description, in connection with the accompanying drawings, is a specification, like reference characters on the 10 drawings indicating like parts in the several figures.

This invention relates to machines for use in the manufacture of boots and shoes, and in particular to machines for forming staple-like fastenings of wire and for driving them 15 through the upper and innersole to secure these parts together.

The invention is herein illustrated as embodied in a machine of the same general 20 type as those disclosed in United States Letters Patent No. 246,437, dated August 30, 1881, and No. 389,275, dated September 11, 1888. These machines employ tack-driving mechanism, for use in securing the upper 25 materials to the sole of a shoe, in which the tacks are automatically fed into driving position and are driven by devices which are caused to operate by pressure of the shoe against an abutment.

30 The present invention has for one of its objects to apply automatic mechanism which is caused to operate similarly to those mechanisms disclosed in the above patents, by pressure of the shoe against an abutment, 35 for forming staples of fine wire and for driving them through like parts of the shoe. These staples may either be employed as the temporary fastenings for holding the lasted upper to the innersole, or they may be employed 40 as the permanent fastenings for use in securing the upper of a turn shoe to the rib of its sole.

With the above object in view, an important feature of the invention consists in 45 the combination with mechanism for forming staples of fine wire or similar stock and for driving such staples, of means which is movable by pressure of the shoe thereagainst for causing said mechanism to operate, it 50 being within the contemplation of the invention to form and drive one, or any other desired number of staples, at each cycle of the machine's operation.

Another feature of importance is comprised 55 in a device for clenching the ends of

the staples against the inner side of the rib, and which is automatically moved into 30 clenching position when the pressure of the shoe is applied to the nozzle through which the staples are driven, and is carried out of such position when such pressure is released by the act of removing the shoe from engagement with the nozzle.

Other important features, such as the details of construction and combinations of 35 parts comprised in the machine which is herein illustrated as the preferred embodiment of the invention, will be more fully set forth in the following description and claims.

In the drawings: Figure 1 illustrates the machine in side elevation; Fig. 2 is an enlarged, perspective view, showing diagrammatically, some of the principal operating parts of the machine, and the fore part of a 70 shoe in position to control the staple-forming and driving devices; Fig. 3 is a detail view showing the nozzle and staple clencher in the positions that they occupy relatively to the parts of the shoe through which 75 staples are driven, just prior to the driving of a staple; Fig. 4 is a detail, perspective view of the staple-forming devices; and Fig. 5 is a front elevation of the machine.

The machine frame includes a suitable 85 base from which extends a standard A, supporting a head B. A driving shaft 1 is rotatably sustained in bearings carried by the head B and supports a loose pulley 3 which may receive power through a belt from any 90 suitable source. The shaft 1 also has fast thereon the cams 2 and 4 by means of which the wire feeding, and staple-forming mechanisms are operated, and said shaft also carries a disk 22 having a crank pin 22^a which 95 is connected with a driver bar 24 through a cross head 24^a. The driver bar is guided for vertical movements in suitable guides carried by the machine frame, and carries a staple driver 26 which slides in a groove 100 formed partly in a staple-forming block 10, and partly in the nozzle 13 through which the staples are driven, as will be hereinafter more fully explained. The wire for forming the staples is supplied by a reel w which 105 is supported from a rigid bracket extending rearwardly from the frame of the machine, the wire passing from the reel forward through a guide 28 and thence passing between the adjacent grooved peripheries of 110

a feed wheel 8 and an idler wheel 9, the latter being journaled intermediate the ends of a lever 11 which is pivoted at one end to the frame and at its opposite end is acted upon by the spring 32 which presses the idler 9 yieldingly against the feed wheel 8. The wire is fed forward by the feed wheel through a curved guideway 18, and thence between the cutter blades 14 and 16 and in position to be formed into staples by the anvil 12 and the rear edge portion of the staple-forming block 10, as shown in Figs. 2 and 4.

The staple-forming block 10 reciprocates in suitable guideways carried by the frame, and is constructed with separated wire-engaging portions arranged to bend the wire over the anvil 12 and form it into U-shaped staples. A section of wire of suitable length to form each staple is cut off from the main strand upon each downward movement of the block by the shear blades 14 and 16, the former of which is supported by the frame of the machine, while the latter is carried by the block 10. The block carries a rack 30 which is engaged by a segmental rack 34 carried at one end of a rock-shaft 6, supported in bearings on the frame. The opposite end of this shaft carries a pinion 38, which is in mesh with a segmental rack 40 on one arm of a bell-crank 41 which is fulcrumed to the frame and carries at the end of its other arm a cam roll which runs in the cam groove of the face cam 2, fast on the drive shaft 1. These parts are preferably so designed that a single reciprocation will be imparted to the block 10 for each complete rotation of the cam 2. The anvil 12 is provided with rack teeth engaging a pinion 42 on a rock-shaft 44 which is supported in bearings carried by the frame. The upper end portion of the shaft 44 sustains a rigid crank 46 whose outer end is slotted to receive a slideable block 46a pivoted to one arm of a bell-crank 48, which is fulcrumed to the frame and carries at the end of its other arm a cam roll that runs in the groove of the cam 4, fast on the shaft 1.

The wire feed wheel 8 is fast to one end of a shaft 50, mounted in bearings carried by the frame. A ratchet 52 is fast to the other end of the shaft 50, and a pawl-carrier 54, turning loosely on the shaft, carries spring-pressed pawls 56 that engage the ratchet and serve, when the carrier is oscillated, to impart a step-by-step rotation to the feed wheel 8 in a direction to feed the wire forward. The pawl carrier is provided with teeth that mesh with the teeth of a segmental rack 58 formed at the end of a crank arm 60 that is fast to, and receives oscillating motion from, the rock-shaft 44. The parts just described are so constructed, arranged and related in their movements, that

each time the shaft 44 is turned to advance the anvil 12 in position for forming a staple the feed wheel 8 will be rotated the required distance to feed forward a length of wire sufficient for the staple. In the illustrated machine, a full cycle of operation, which includes the feeding forward of a length of wire, the formation of a staple therefrom, the driving of the staple into the work and the return of the several parts to position to repeat these several functions when the machine comes to rest, is caused to take place each time the shoe is pressed against the nozzle 13. To this end, mechanism which may, and preferably will be, substantially like that shown in either of the Letters Patent above referred to, is provided for tripping a one-revolution clutch by pressure applied to the nozzle through the shoe, which clutches the loose pulley to the shaft 1 and, thereafter, upon a completion of the cycle, the pulley is automatically unclutched and the machine is brought to a stop.

As indicated by dotted lines in Fig. 1, a tapering clutch member 62, which slides on the driving shaft but is constrained to rotate therewith through a feather, or other like connection, is shaped to fit a recess in the loose pulley, and when these parts are in engagement the pulley is clutched to the shaft. The member 62 has connection through an annular groove with two diametrically arranged pins carried by a yoke 63 which is supported by a lever 64, fulcrumed at its lower end to the machine frame. A spring 66 extends from the lever 64 to a bracket carried by the frame, and tends to move the clutch member 62 into engagement with the loose pulley. A lever 67, pivoted to the frame, is provided at its upper end with a cam roll 68 that runs in the groove in cam 4. The lever 67 supports a trip-lever 170, having at one end a shoulder to engage the lever 64 and hold the clutch out of engagement with the loose pulley, and a spring 172 Fig. 5 extends from the lever 170 to a fixed part of the frame and normally tends to maintain the parts in such relation. An extension from the nozzle 13 carries a bell-crank 174, which is yieldingly held against a stop by a spring 175, and is arranged immediately below an offset portion of the forward end of the lever 170, all as substantially disclosed in the prior Letters Patent No. 246,437. A movable brake shoe 77 carried by the yoke 63, has a conical recess to engage a co-operating conical brake member 78 which is fixed to and rotates with the shaft 1, and when the member 62 is moved out of engagement with the loose pulley the brake members are caused to engage immediately thereafter, thus bringing the machine to a stop.

The ends of the staples that are driven through the shoe materials are clenched

against a curved clenching anvil 70, which is carried by a shaft 71, pivotally supported from a bracket 72 extending from the frame. The pivot shaft 71 has an eccentric bearing 71^a, Fig. 3, which, through a ring 71^b, Fig. 2 secured thereto may be turned to adjust the anvil 70 relatively to the end of the nozzle 13 so as to properly position these parts for variations in thickness of sole lips, or other shoe parts through which the staples are to be driven, and then clenched. An arm 74 having an inclined slot 75 is carried rigidly by the shaft 71, and a lever 76 fulcrumed at an end 77 to a fixed part of the frame, is pivotally joined at 78 to the nozzle 13, and at its free end carries a pin 79 that works in the slot 75. By this construction, the pressure against the nozzle which is exerted by a shoe will effect, through the lever 76 and connections, a combined inward and upward movement of the anvil 70 to position its clenching end against the inner side of the rib on a sole at a point immediately opposite the end of the nozzle from which the staples are driven, so as to be in position to clamp the staples, as shown in Fig. 3.

The shoes may be presented to the machine by hand, if desired, but preferably a jack will be employed of the construction illustrated in Fig. 1, in order to afford a firm and reliable support for the shoe and to relieve the operator of unnecessary strain. A lever 80, fulcrumed at 81 to the base of the machine, supports a standard 82 to which is connected by a transverse pivot 83 an angular jack arm 84. A rigid extension 82^a of the standard has a segmental slot 85 to receive a clamping bolt 87 which passes through the arm 84 and serves to clamp the jack in the different positions of adjustment to which it may be moved about the pivot 83, but when shanks as well as foreparts of shoes are to be lasted and stapled the bolt 87 will be left loose so that the shoe can be moved toward and from the machine about the pivot 83. The shoe-supporting plate 88 is connected with the arm 84 by a pivot pin 90 which lies substantially at right angles to the pivot 83, and the plate is turned about the pin 90 as an axis as the shoe is moved around to present different portions of the upper to the staple-driving mechanism. A block 92 is supported, with capacity for longitudinal adjustment, on the plate 88, and a toe rest 94, pivoted to the block, engages the upper portion of the shoe near the toe end. A pivotally supported spring-pressed heel pin 96 is connected to the opposite end of the plate 88, and co-operates with the toe rest in supporting a shoe in position to present the edge of the upper to the lower end of the nozzle 13, as shown in Fig. 1.

The jack-supporting lever 80 has a laterally-projecting stud 98 which is engaged

by an edge portion of a treadle lever 20, fulcrumed at 102 to a fixed bracket. The rear end of the lever 80 supports a rod 103, which is guided vertically in a hole through a lug 101, rigid with the frame; and a spring 104 extends from the frame base to an adjustable nut on the rod 103. Pressure of the operator's foot upon the treadle carried by the lever 20 serves to raise the jack from lowered, to raised position, and to press a shoe 75 carried by the jack against the nozzle 13; and the weight of the jack and its associated parts is sufficient to return the jack to lowered position again when the operator removes his foot from the treadle. If the operator should allow the jack to fall suddenly the descent of the jack will be cushioned by the spring 104, and unnecessary shock, with possible injury to the parts of the machine, thereby prevented. This spring also acts to 85 partially counterbalance the weight of the jack.

In the use of the machine, a last with a sole, upper, and lining properly assembled thereon is placed on the jack, with the upper face of the forepart engaging the toe rest 94, and the jack pin 96 within the jack pin hole, while the pin is urged forwardly by its spring and presses the shoe against the toe rest. The operator, after having adjusted the jack so that the shoe will be presented in proper relation to the machine, then steps on the treadle, raising the jack until the shoe engages the end of the nozzle 13 at substantially the point shown in Fig. 3, 100 and continued movement of the jack will then raise the nozzle, causing the anvil 70 to be swung underneath the sole rib, and opposite the nozzle, and also tripping the clutch-retaining lever 170. The spring 66 105 will then effect engagement of the clutch member with the loose pulley, and the mechanism of the machine will feed forward and cut off a length of wire, form it into a staple, and drive the staple through the upper, 110 lining and rib of the shoe, and clench its ends against the anvil 70. The described machine parts will then be returned to position for repeating these several operations, and the cam 4 will cause the lever 67 to 115 reversely move the lever 64, thereby unclutching the shaft, applying the brake, and bringing the machine to rest. After each fastening is driven the operator lowers the shoe to a slight extent, turns it about the 120 axis 90 to present another portion of the work to the driving mechanism, and raises the shoe to again actuate the staple-forming and driving mechanism, a complete cycle of the machine's operation being performed 125 for each successive fastening that is inserted in the work.

The right is reserved to make such changes in the form, proportions or relative arrangement of the several parts here- 130

in shown as illustrative of a preferred embodiment of the invention, as will fall within the scope of the following claims.

Having thus described my invention, what I claim as new and desire to secure by Letters Patent of the United States is:—

1. In a machine of the class described, the combination with mechanism for forming and driving staples, and power operating mechanism therefor, of means actuated by pressure applied through the work for causing said first-mentioned mechanism to be operated by the last-mentioned mechanism, and a staple clenching anvil arranged for movement into clenching position before the power mechanism is connected with the forming and driving mechanism. 70
2. In a machine of the class described, the combination with mechanism for forming and driving staples, and power operating mechanism therefor, of means actuated by pressure applied through the work for causing said first-mentioned mechanism to be operated by the last-mentioned mechanism, and a staple clenching anvil arranged for movement toward and also along the plane of the face of the work into clenching position by the pressure applied through the work. 80
3. In a machine of the class described, the combination with mechanism for forming and driving staples, of a movable abutment through which the staples are driven, means actuated by pressure of the work against the abutment to cause said mechanism to operate, and an anvil to clamp the staples movable into operative position when pressure is applied to said abutment. 90
4. In a machine of the class described, the combination with mechanism for driving fastenings, of a nozzle for engaging the work and through which the fastenings are driven, a clenching anvil, and means actuated by pressure of the work against said nozzle to cause said mechanism to operate and to move said anvil into position for clenching the fastenings. 100
5. In a machine of the class described, the combination with mechanism for driving fastenings, and power operating mechanism therefor, of a nozzle for engaging the work and through which the fastenings are driven, a clenching anvil, and means actuated by pressure of the work against said nozzle first to move said anvil into position for clenching the fastenings and then to start the power mechanism for operating the driving mechanism. 110
6. In a machine of the class described, the combination with mechanism adapted for driving fastenings through a shoe upper and the rib of the sole, of a movable nozzle arranged to force the upper against the rib and having an aperture through which the fastenings are driven, a clenching anvil, 120
- means actuated by pressure of the shoe against said nozzle to effect the operation of said mechanism, and means also actuated by said pressure to move said anvil into clenching position against the opposite side of the rib. 125
7. In a machine of the class described, the combination with fastening-driving mechanism, of a movable nozzle through which the fastenings are driven, connections to effect actuation of said mechanism by pressure of a shoe against the nozzle, an anvil movable into and out of position to clamp fastenings, and connections between said nozzle and anvil constructed to cause the anvil to move into clenching position when pressure is applied to the nozzle. 130
8. In a machine of the class described, the combination with fastening-driving mechanism, of a movable nozzle through which the fastenings are driven and connections to effect the actuation of said mechanism when the nozzle is moved by pressure applied through a shoe, a clenching anvil, and connections between said nozzle and anvil constructed to cause the anvil to move into position to clamp fastenings when pressure is applied to the nozzle and to move out of such position when the nozzle is relieved of pressure. 135
9. In a machine of the class described, the combination with a movable nozzle through which fastenings are driven, of a pivotally-supported clenching anvil, an arm connected with said anvil and having an inclined slot, and a lever fulcrumed at one end and at its other end carrying a pin engaging said slot, said lever being connected with said nozzle. 140
10. In a machine of the class described, the combination with a movable nozzle through which fastenings are driven, of a clenching anvil, a pivot supporting said anvil, an adjustable eccentric bearing for said pivot, and connections between said nozzle and anvil constructed to effect movement of the anvil into clenching position when pressure is applied to the nozzle, and to permit the anvil to move out of such position when the nozzle is relieved of pressure. 145
11. In a machine of the class described, the combination with mechanism for forming and driving fastenings, of a clenching anvil, a pivot supporting said anvil, an adjustable eccentric bearing for said pivot, and means constructed to effect movement of the anvil into clenching position in response to pressure of the work. 150
12. In a machine of the class described, the combination with a movable nozzle to engage the work and through which fastenings are driven, of fastening-inserting mechanism controllable by said nozzle, a clenching anvil arranged for engaging an opposite 155

side of the work, a pivotal support for the anvil laterally removed from said nozzle, and connections between said nozzle and anvil to effect, through the nozzle, movements of the anvil into and out of clenching position.

13. In a machine of the class described, the combination with a movable abutment, of fastening-inserting mechanism controllable by pressure on said abutment applied through a shoe, and a jack constructed to present a shoe with its sole substantially parallel with the direction in which the fastenings are driven and to permit the shoe to be turned about an axis substantially perpendicular to the plane of the shoe bottom.

14. In a machine of the class described, the combination with mechanism constructed and arranged to drive fastenings through a shoe upper and the rib of a sole, of a jack constructed to present a shoe with its sole substantially parallel with the direction in which the fastenings are driven and to permit the shoe to be turned about an axis substantially perpendicular to the plane of the shoe bottom.

15. In a machine of the class described, the combination with a movable abutment, of fastening-inserting mechanism controllable by pressure on said abutment applied through a shoe, a jack constructed to permit a shoe to be turned about an axis substantially perpendicular to the shoe bottom for presenting different portions of the shoe edge to said mechanism, and treadle means to raise the jack and press the shoe against said abutment.

16. In a machine of the class described, the combination with a movable abutment, of fastening-inserting mechanism controllable by pressure on said abutment applied through a shoe, a jack constructed to present a shoe with its sole substantially parallel with the direction in which fastenings are driven, treadle means to raise the jack and press the shoe against said abutment, and means to cushion the reverse movement of said jack.

17. In a machine of the class described, the combination with fastening-inserting mechanism and means to cause said mechanism to operate by pressure applied through the work, of a jack, a lever having connection on one side of its fulcrum with said jack, a treadle-actuated lever arranged for engagement with said first-named lever to raise the jack and actuate said means, and a spring having connection with said first-named lever on the other side of its fulcrum for cushioning the descent of the jack.

18. In a machine of the class described, the combination with fastening-inserting

mechanism, of a jack comprising an arm, a plate supported from the arm and carrying means to engage the fore-part and the heel-part of a last having shoe materials assembled thereon, means connecting said plate and arm for permitting the shoe to be turned about an axis substantially perpendicular to the plane of the shoe bottom for presenting different portions of the shoe edge in position to receive fastenings, means for raising the jack, and means actuated by the pressure of the shoe when the jack is raised for initiating the operation of said mechanism.

19. In a machine of the class described, the combination with fastening-inserting mechanism the operation of which is controlled by pressure of the work, of a jack comprising an arm, a plate supported from the arm and carrying means to engage the fore-part and the heel-part of a last having shoe materials assembled thereon, means connecting said plate and arm for permitting the shoe to be turned about an axis substantially perpendicular to the plane of the shoe bottom for presenting different portions of the shoe edge in position to receive fastenings, and means for raising the jack to initiate the operation of the fastening-inserting mechanism.

20. In a machine of the class described, the combination with means for driving fastenings, of a movable nozzle through which the fastenings are driven, a clenching anvil, and means to cause said anvil to move into operative position when pressure is applied to said nozzle.

21. In a machine of the class described, the combination with means for driving fastenings, of a movable nozzle through which the fastenings are driven, an anvil movable into and out of position to clamp fastenings, and connections between said nozzle and anvil constructed to cause the anvil to move into clenching position when pressure is applied to the nozzle.

22. In a machine of the class described, the combination with a movable nozzle to engage the work and through which fastenings are driven, of a clenching anvil arranged for engaging the opposite side of the work, a pivotal support for the anvil laterally removed from said nozzle, and connections between said nozzle and anvil to effect, through the nozzle, movements of the anvil into and out of clenching position.

In testimony whereof I have signed my name to this specification in the presence of two subscribing witnesses.

JAMES CAVANAGH.
